Primary Examiner — Kendra Leslie Hamilton*Assistant Examiner* — Elizabeth S Struble(74) *Attorney, Agent, or Firm* — NORTON ROSE
FULBRIGHT CANADA LLP(57) **CLAIM**

The ornamental design for a spa, as shown and described.

DESCRIPTION

FIG. 1 is a top, front, left perspective view of a spa, showing my new design;

FIG. 2 is a top plan view thereof;

FIG. 3 is a front elevation view thereof;

FIG. 4 is a rear elevation view thereof;

FIG. 5 is a right side elevation view thereof; and,

FIG. 6 is a left side elevation view thereof.

In the drawings, the equal-length broken lines depict portions of the spa that form no part of the claimed design.
